UNITED STATES PATENT OFFICE.

WILLIAM HERZOG, OF GARFIELD, NEW JERSEY.

BUTTON-GRINDING MACHINE.

1,032,829.

Specification of Letters Patent. Patented July 16, 1912.

Application filed September 2, 1911. Serial No. 647,330.

To all whom it may concern:

Be it known that I, WILLIAM HERZOG, a citizen of the United States, and a resident of Garfield, in the county of Bergen and State of New Jersey, have invented a new and Improved Button-Grinding Machine, of which the following is a full, clear, and exact description.

My invention relates to a button-making machine, and a particular object of my invention is to form perfect buttons from "seconds" by means of a machine of simple construction containing relatively few parts, and which is adapted to form buttons of different shapes and sizes.

With the above and other objects in view, as will more fully hereinafter appear, the present invention consists in certain novel details of construction and arrangement of parts hereinafter fully described, illustrated in the accompanying drawings, and more particularly pointed out in the appended claims.

Reference is to be had to the accompanying drawings, forming a part of this specification, in which similar characters of reference indicate corresponding parts in all the figures and in which—

Figure 1 is a plan view looking down upon a preferred embodiment of my invention; Fig. 2 is a front elevation of the same with a button in position on the grinding wheel; Fig. 3 is a view similar to Fig. 2 but showing the button-carrying spindle in retracted position; Fig. 4 is a transverse sectional view taken on the line 4—4 of Fig. 1 and looking in the direction of the arrow; Fig. 5 is a view similar to Fig. 4 but showing the carriage swung into position to bring the button in engagement with the grinding wheel; Fig. 6 is a detailed end view of a former cam connection; Fig. 7 is a detailed side elevation, partly in section, of the button-carrying shafts; Fig. 8 is an end view of one of the shafts shown in Fig. 7 and looking in the direction of the arrow *a*; Fig. 9 is an end view of the opposite co-acting shaft looking in the direction indicated by the arrow *b*; Fig. 10 is an elevation of a former cam; Fig. 11 is a plan view of the button formed by using the former cam shown in Fig. 10; Fig. 12 is a different form of former cam to that shown in Fig. 10; Fig. 13 is a view similar to Fig.

7 but showing the shafts used in forming flat-face buttons; Fig. 14 is an end view of the recessed shaft shown to the left of Fig. 13; Fig. 15 is a transverse section through the axis of this shaft; Fig. 16 is a side elevation of a shank button; and Fig. 17 is an edge view of a section of a grooved grindstone.

Described more in detail, a bed 19 of any suitable construction has extending upwardly from opposite ends thereof, a pair of standards 20, in the upper ends of which is journaled a drive shaft 21. Loosely mounted upon one end of the drive shaft is a loose pulley wheel 22 and a driving pulley wheel 23, which driving wheel is actuated by belting 24 from any suitable source of power. Loosely mounted centrally upon the shaft 21, is a swinging carriage 25, which carriage comprises a base plate 26 positioned below and extending parallel with the shaft 21. Projecting upwardly from this base plate and loosely mounted on the shaft 21, are four supporting arms 27, 28, 29 and 30. The upper ends of these arms terminate in bearing bosses 31, 32, 33 and 34, and extending in alignment through the bosses is a chuck spindle 35. Rigidly mounted upon the spindle 35 between the bosses 31 and 32, is a gear 36 permanently in mesh with a gear 37 rigidly mounted upon the shaft 21, and correspondingly, between the bosses 33 and 34 and contacting with the boss 33, is a gear 38 permanently in mesh with a relatively broad gear 39 rigidly mounted upon the shaft 21. It will be seen that by this construction motion is transmitted from the shaft 21 to the spindle 35. The spindle 35 is interrupted between the central bearings 32 and 33, to form a chuck member 40, the end of which is reduced, which reduced end has screw threads 41 thereon (see Fig. 7) and has a slot 42 extending diametrically through the end 43; said slot being enlarged on opposite sides of the center thereof to form a pair of spaced apart apertures 451; engaging the screw threads 41 is a nut 44, and inserted in the apertures 451 are a pair of spaced-apart pins 45, which pins are held rigidly in place by means of the chuck formed by the nut 44 engaging the split threaded end of the chuck member 40. These pins are constructed to pass through

the eyes 46 of the "seconds." The opposite member 47 of the spindle 35 has a pair of spaced-apart apertures 48 in the edge thereof, into which apertures are positioned the pins 45. In order to facilitate the ejection of the pins, a slot 49 is positioned in the end of the member 47 in rear of the apertures 48, and in order to separate the chuck member 40 from the member 47, the latter member is slideable longitudinally in the bearing bosses 33 and 34 against the action of a coil spring, 50, which coil spring has one end bearing against a washer 51 adjacent the bearing 34, the other end of which spring is in engagement with the side of the gear 38. In order to bring the button 52 carried by the pins 45 into engagement with the grinding wheel or stone 53 hereinafter described, an arm 54 has one end pivoted by means of a pin 55 to an extension 56 projecting integrally from the rear of the face plate 26. This arm extends some material distance to the front of the machine and terminates in a convenient handle 57, so that by raising the arm 54 by means of the handle 57, the carriage 25 may be swung on the shaft 21, to bring the button 52 into variable engagement with the grinding wheel 56. The extent of this engagement may be varied by means of a bolt 58 passing through the extension 56 and adapted to bear on the top of the bed 19. This bolt is locked in position by means of a lock nut 59. By means of this same arm 56, the belting 24 may be thrown from the loose pulley 22 to the actuating pulley 23, and vice versa, by means of a belt-throw 60, which belt-throw comprises a strap-engaging loop 61 rigidly mounted on one end of a lever 62, to the other end of which lever is attached a bar 63 extending along the front of the machine preferably on a level with the bed 19 and having a pair of upwardly-extending fingers 64 disposed on opposite sides of the arm 54. The bar 63 is guided in position by means of a guiding bracket, from which guiding bracket extends a pair of pins 56 disposed about opposite sides of the bar. It will be seen that by this construction the movement of the arm 54 to the right or left on its pivotal connection 55 will throw the gear 38 and belt shifter 60 into operative or inoperative position.

55 To permit the application of the button to the revolving grindstone 53, a vertically-extending plate 660 is rigidly mounted on the bed 19 on the opposite side of the carriage 25 from the extension 56, and has an L-shaped slot 67 therein, in which slot is adapted to be positioned the arm 54. It will be seen that when the arm 54 is in the horizontal portion 68 of the slot, as shown more particularly in Fig. 3, the belt 24 is on the loose pulley and this plate 660 locks the carriage in its inoperative position with reference to the grindstone 53 when the button is not rotating.

56 In order to bring the button into engagement with the grindstone, it is necessary to bring the member 54 into the vertical portion of the slot 67, but this same movement will automatically throw the belt on to the actuating pulley 23. It is desirable to withdraw the button from the revolving grindstone and to throw the belt on the loose pulley simultaneously, and, at the same time, to separate the members 40 and 47, to remove the button without waiting for the spindle 35 to come to a full stop. This entire operation may be performed simultaneously by the actuation of the arm 54, and for this purpose, an L-shaped lever 69 is fulcrumed by means of a pin 70 to the plate 660 and to one side of the vertical portion of the L-shaped slot 67. The upper end of the lever 69 is offset toward the carriage, as shown more particularly in Fig. 4, and pivotally mounted in the upper end of said lever is a roller 71 maintained in engagement with the front face of the gear 38 by means of a coil spring 72, which coil spring has one end attached to the plate 660 on the side of the slot 67 opposite the pin 70, the other end of which spring is attached to the outer end of the horizontal leg 73 of the lever 69, as shown more particularly in Fig. 2. This horizontal leg 73 extends across the horizontal portion 68 of the slot 67, so that forcing the arm 54 to the right, will swing the lever 69 into the position shown in Fig. 3, forcing the gear 38 against the action of the spring 50, thereby disengaging the apertures 48 from the pins 45, as shown in full and dotted lines in Fig. 7, and permitting the removal of the button 52. It will be seen by this construction, assuming the button to be in engagement with the grinding wheel 53, that the depressing of the arm 54 in the horizontal portion of the slot 67, will withdraw the button from its engagement with the wheel, and then moving the arm to the right into the horizontal portion of the slot, will simultaneously shift the belt 24 to the loose pulley and will withdraw the member 47 from its engagement with the pins 45. By means of this arm 54, the button is maintained manually in contact with the grindstone 53, but should it be desired to give this button any particular shape, a former cam 74 of suitable configuration, such as shown in Figs. 6, 10 and 12, is rigidly mounted upon the outer end of the member 47, which former cam is adapted to engage a roller 75 rotatably mounted upon the upper end of a standard 76 extending upwardly from the bed 19.

57 The grindstone 53 is mounted in transverse alignment with the button 52 and is

70 75 80 85 90 95 100 105 110 115 120 125 130

58 59 60 61 62 63 64 65 660 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

preferably mounted at one end of a shaft 77, which shaft is journaled in a floating chuck 78 vertically adjustable in a standard 79 by means of a hand wheel 80, which standard is transversely adjustable on a track 81 extending rearwardly from the bed 19. The shaft 77 is rotated independently of the rotation of the drive shaft 21, by means of a pulley 82 rigidly mounted on the shaft 77, which shaft is actuated by means of a belting 83 driven from a suitable source of power. It is to be understood that by this construction the grindstone may be adjusted in position relative to the button.

15 The invention has been described with reference to a button having eyes extending therethrough, but the members 40 and 47 may be modified to carry a plain-faced button such as is shown in Figs. 13 and 16. 20 For this purpose the end of the member 40 is recessed to form a pocket 84, the edge of which pocket is corrugated to form a crown edge 85 adapted to engage one face of the button. The end of the member 47 is similarly recessed, into which recess is disposed a rubber or fabric cushion 86 held in position by means of a screw 87, which cushion is adapted to bear on the opposite face of the button 52. It will be seen by this construction that the spring 50 acting on the member 47 forces the button into engagement with the crown head 85, forming a clutch to hold the rotating button in engagement with the grinding wheel 53.

25 Where it is desired to give a rounded edge to the buttons, a grindstone having a groove 88 (see Fig. 17) in its periphery, may be substituted for the square edged stone shown in the other figures.

30 Having thus described my invention, I claim as new and desire to secure by Letters Patent:

1. In a button-grinding machine, a bed, a pair of standards projecting upwardly from said bed, a power shaft journaled in said standards, a pair of pulleys, one rigidly and one loosely mounted on said shaft, a carriage loosely mounted on said shaft and adapted to be rocked thereon, a two-part 45 chuck spindle journaled in the upper part of said carriage, means carried by said spindle to removably mount a button between the two parts, a gear connection between said shaft and each part of said spindle, a 50 rotating grindstone stationarily mounted in transverse alinement with said button, and an arm pivoted to said carriage by means of which said carriage is rocked to bring said button into engagement with said 55 grindstone.

2. In a button-grinding machine, a rotating grindstone, a carriage, a chuck spindle rotatably mounted in said carriage, said chuck spindle adapted to carry a button, 60 and means for moving said carriage trans-

versely of the length of said spindle to bring said button into engagement with said grindstone.

3. In a button-grinding machine, a stationarily positioned rotating grindstone, a 70 rocking carriage, a button-carrying chuck spindle journaled in said carriage, means for conveying motion to said spindle, said means constituting the pivoting support for said carriage; and an arm extending from 75 said carriage adapted to manually rock the same to maintain said spindle in juxtaposition to said grindstone.

4. In a button-grinding machine, a power shaft, a carriage mounted to rock on said shaft, a chuck spindle journaled in said carriage, gear connections between said shaft and said chuck spindle, a pair of pulleys mounted on said power shaft, a power belting engaging one of said pulleys, one of 80 said pulleys being loose and the other rigidly keyed to said shaft, a handle pivoted to said carriage to rock the same, and a belt-throwing mechanism actuated by said handle, to move the belting from one to the 85 other of said pulleys.

5. In a button-grinding machine, a power shaft, a carriage mounted to rock transversely on said shaft, a stationarily positioned standard, a chuck carried thereby, 95 and a grindstone positioned thereon, means for rocking said carriage toward said grindstone, and means acting on said chuck for varying the position of said grindstone relative to said carriage.

6. In a button-grinding machine, a power shaft, a carriage mounted to rock on said shaft, a chuck spindle journaled in said carriage, said chuck spindle comprising two members, one of said members being slidable 105 longitudinally with reference to the other, and means carried by said two members, to hold a button on said spindle.

7. In a button-grinding machine, a power shaft, a carriage mounted to rock on said shaft, a chuck spindle journaled in said carriage, said chuck spindle comprising two members, one of said members being slidable longitudinally with reference to the other, means carried by said two members, to hold 110 a button on said spindle, means by which said carriage is rocked, and mechanisms actuated by said means to separate said members whereby the button may be disengaged from said spindle.

8. In a button-grinding machine, in combination, a grindstone, a power shaft, a carriage mounted to rock on said shaft, a clutch spindle journaled in said carriage, said clutch spindle comprising two parts, 115 means for mounting a button between said parts, means connecting said power shaft with each of said parts, whereby each part is rotated independently of the other, an arm pivoted to said carriage by means of 120 125 130

- which the carriage is rocked to bring the button into engagement with said grindstone, and means actuated by said arm, to separate one of said parts from the other to remove the button.
9. In a button-grinding machine, in combination, a grindstone, a power shaft, a carriage mounted to rock on said shaft, a clutch spindle journaled in said carriage, said clutch spindle comprising two parts, means for mounting a button between said parts, means connecting said power shaft with each of said parts, whereby each part is rotated independently of the other, an arm pivoted to said carriage by means of which the carriage is rocked to bring the button into engagement with said grindstone, means actuated by said arm to separate one of said parts from the other, to remove the button, and means maintaining said parts in engagement with each other.
10. In a button-grinding machine, a button-carrying spindle, a grindstone, means for bringing the button carried by said spindle into engagement with said grindstone, a former cam carried by said spindle, and a stop adapted to be engaged by said cam whereby the relation of said button to said grindstone is varied to give the button the configuration of the cam.
11. In a button-grinding machine, a power shaft, a carriage loosely mounted on said shaft, a two-part button-carrying spindle mounted in said carriage, means for conveying motion from said shaft to said spindle, a grindstone, means for rocking said carriage to bring the button carried by said button-carrying spindle into engagement with said grindstone, and means for locking said carriage in an inoperative position.
12. In a button-grinding machine, a power shaft, a carriage loosely mounted on said shaft, a two-part button-carrying spindle mounted in said carriage, means for conveying motion from said shaft to said spindle, a grindstone, means for rocking said carriage to bring the button carried by said button-carrying spindle into engagement with said grindstone, means for locking said carriage in an inoperative position, and means for separating the parts of said button-carrying spindle while in said inoperative position.
13. In a button-grinding machine, a spindle comprising two parts separated in order to carry a button therebetween, one of the adjacent ends of said parts being recessed transversely and screw-threaded exteriorly, a pair of pins adapted to be mounted in said recess, and a nut engaging said screw threads to force the sides of the recess together, to hold said pins rigidly in position, the opposing end of the other part having a pair of apertures therein adapted to receive the free ends of said pins.
14. In a button grinding machine, a two part button carrying spindle, one of said parts sliding longitudinally with relation to the other, means carried by the spindle to removably hold a button thereon, a grinding wheel, means for manually holding said button in engagement with said grinding wheel, and mechanism actuated by said means for separating the parts of the spindle to permit the removal of the button.
15. In a button grinding machine, a two part button carrying spindle, one of said parts sliding longitudinally with relation to the other, means carried by said spindle to removably hold a button thereon, a grinding wheel, means for manually holding said button in engagement with said grinding wheel, mechanism actuated by said means for separating parts of said spindle to permit the removal of the button, and a belt throwing device actuated by said mechanism for disconnecting said spindle from the source of the power.
16. In a button grinding machine, a two part button carrying spindle, one of said parts sliding longitudinally with relation to the other, means carried by the spindle to removably hold a button thereon, a driving shaft extending parallel to the spindle, and independent gear connections between the two parts of the button carrying spindle and the driving shaft, one of said geared connections permitting a longitudinal movement of a spindle part without disconnecting said gear connections.
17. In a button grinding machine, a two part button carrying spindle, one of said parts sliding longitudinally with relation to the other, means comprising a plurality of button engaging pins carried by one part of said spindle and having a sliding connection with the other part of said spindle, a driving shaft extending parallel to said spindle, and independent gear connections between said spindle parts and said driving shaft.
- In testimony whereof I have signed my name to this specification in the presence of two subscribing witnesses.
